[57] CLAIM

The ornamental design for a cabinet for an electronic
ignition analyzer, as shown and described.

DESCRIPTION

FIG. 1 is a right front perspective view of a cabinet for
an electronic ignition analyzer showing my new design;
FIG. 2 is a front elevational view thereof, the rear being
flat, plain, and unornamented;

FIG. 3 is a top plan view thereof;

FIG. 4 is a left side elevational view thereof.

Fig. 1.Fig. 2.Fig. 4.Fig. 2.
